UNITED STATES PATENT OFFICE

134,472

DESIGN FOR A HEATER UNIT

Elias B. Barnes, Elkhart, Ind.

Application May 25, 1942, Serial No. 106,993

Term of patent 14 years

To all whom it may concern:

Be it known that I, Elias B. Barnes, a citizen of the United States of America, residing at Elkhart, in the county of Elkhart and State of Indiana, have invented a new, original, and ornamental Design for a Heater Unit, of which the following is a specification, reference being had to the accompanying drawing, forming part thereof.

In the drawing:

Fig. 1 is a side elevational view of a heater unit showing my new design;

Fig. 2 is a front elevational view of my heater; and

Fig. 3 is a plan view thereof.

The back of the heater is substantially plain, and the other side is similar to the side shown in Fig. 1.

I claim:

The ornamental design for a heater unit, as shown and described.

ELIAS B. BARNES.
